UNITED STATES PATENT OFFICE.

MIKE FALCO, OF CANONSBURG, PENNSYLVANIA.

PENHOLDER.

Application filed July 1, 1926. Serial No. 119,920.

This invention relates to an improved pen holder and it has more particular reference to novel means for maintaining a renewable pen in place.

5 The ordinary holder is of such construction as to make it necessary to pull the pen out in order to put a clean and new one in place. This is not only inconvenient in that the pen becomes stuck in place, but 10 since the pen has become coated with ink, the user is called upon to soil his fingers.

15 What I propose to do is to provide novel means for holding the pen in place, this means being such that it facilitates insertion and removal, in fact, allows the soiled pen to literally drop out without being touched by the user's fingers.

20 The details and their relative association will become apparent from the following description and drawing.

25 In the drawing:—

Figure 1 is a perspective view of the improved pen holder showing the pen in place.

Figure 2 is a perspective view showing the 30 pen detached.

Figure 3 is a perspective view showing certain of the parts separated.

Figure 4 is a perspective view showing the 35 reduced end of the handle or stem of the pen.

Figure 5 is a perspective view of the stationary ferrule.

40 In the drawing the reference character 1 designates the wooden handle or stem which, as shown in Figure 4 has a reduced outer end portion 2 of tapered cross section. This reduced portion is formed on one side with a longitudinal groove 3. Fitted onto this extension is a metal ferrule 4 of tubular form, the same being tapered from end to end, being formed from a strip of metal having its opposite edges brought together as at 45 to provide a longitudinal locking key for reception in the groove 3. The ferrule is also provided with a circumferential indentation 6 forming an internal rib for reception in a correspondingly shaped groove 7 formed in the aforesaid extension 2. This holds the ferrule in place as represented in Figure 3. One end portion, however projects beyond the extension 2 and the upper half of the same is pressed as indicated at 80 8 to provide a longitudinal seat for reception of the shank of the pen 9.

Surrounding the ferrule 4 is a sleeve 10 and this sleeve is provided at its inner end with an inwardly pressed circumferential retaining bead 11 which fits into the aforesaid depression 6 and provides a rotatable locking connection between the sleeve and the ferrule. From Figure 3 it will be seen that the upper half side of the sleeve is cut away as at 12 to expose the shank of the pen. Moreover, the outer end thereof is beveled somewhat as indicated at 13 to aid 15 in holding the shank in place. The sleeve is of a length substantially equal to the ferrule.

20 In practice, the sleeve 10 is turned so that the slot or elongated opening 12 is in registry with the depression or seat 8 on the ferrule, as shown for instance in Figure 2. Then the shank of the pen 9 is inserted so that it rests in this seat 8. Now, the sleeve is turned to bring the imperforate portion 25 to the position shown in Figure 1. This therefore clamps the pen in place. To remove the pen it is simply necessary to return the sleeve to the position shown in Figure 2, whereby the soiled pen will be allowed 30 to drop out. Obviously, this can be accomplished without soiling one's hands.

35 It is believed that by considering the description in connection with the drawing, a clear understanding of the invention will be obtained, therefore, a more lengthy description is thought unnecessary.

40 While the preferred embodiment of the invention has been shown and described, it is to be understood that minor changes coming within the field of invention claimed 45 may be resorted to if desired.

45 Having thus described the invention, what I claim as new and desire to secure by Letters Patent is:—

50 1. A pen holder provided at its outer end with a reduced extension formed with a longitudinal groove, and a circumferential groove, a metal ferrule fitted on said extension and provided with a longitudinal rib 55 fitted in the longitudinal groove and a circumferential rib fitting into the circumferential groove, the outer end portion of said ferrule being pressed to form a seat for reception of the shank of a pen, a sleeve 60 mounted for rotation upon said ferrule, said sleeve having one half portion cut away to provide an elongated notch opening through

the outer end of the sleeve, said notch serving to release said pen when it is aligned with the shank of the pen.

2. A pen holder provided at its outer end with a reduced extension formed with a longitudinal groove, a metal ferrule formed from a single sheet of metal curved to form a split sleeve the longitudinal edges of which are bent inwardly to form a longitudinal rib, said ferrule fitted on said extension with the rib fitted in said longitudinal groove, the outer end portion of said ferrule being pressed in to form a seat for reception of the shank of a pen, a sleeve mounted for rotation upon said ferrule, said sleeve having one-half portion cut away to provide an elongated notch opening through the outer

end of said sleeve, said notch serving to release said pen when it is aligned with the shank of said pen.

3. A pen-holder provided at its outer end with a reduced extension formed with a longitudinal groove, a ferrule formed from a single sheet of metal bent to form a split sleeve, the longitudinal ends being bent inwardly to form a longitudinal rib, said ferrule fitted on said extension and said rib fitted in said groove, and retaining means on said ferrule for a pen permitting the pen to be removed by allowing it to be literally dropped out.

In testimony whereof I affix my signature.

MIKE FALCO.
